(57) CLAIM

The ornamental design for a medical device display, as shown and described.

DESCRIPTION

FIG. 1 is a front view of the first embodiment of a medical device display showing my new design;

FIG. 2 is an enlarged front view thereof;

FIG. 3 is an enlarged front view of a second embodiment thereof;

FIG. 4 is an enlarged front view of a third embodiment thereof;

FIG. 5 is an enlarged front view of a fourth embodiment thereof;

FIG. 6 is an enlarged front view of a fifth embodiment thereof;

FIG. 7 is an enlarged front view of a sixth embodiment thereof;

FIG. 8 is an enlarged front view of a seventh embodiment thereof;

FIG. 9 is a front view of an eighth embodiment of a medical device display showing my new design; and,

FIG. 10 is an enlarged front view thereof.

The different types of shading shown in FIGS. 3-8 represent a contrast of appearance. The broken line showings of the medical device display are for the purpose of illustrating environmental structure and form no part of the claimed design.
